Specification for Design.

Patented Feb. 20, 1917.

Application filed December 21, 1916. Serial No. 138,268. Term of patent 14 years.

To all whom it may concern:

Be it known that I, WILLIAM A. ROBBINS, a citizen of the United States, residing at Glen Ridge, in the county of Essex and State of New Jersey, have invented a new, original, and ornamental Design for Automobile-Tires, of which the following is a specification.

In the drawing accompanying and forming a part of this specification,

Figure 1 is a plan view of a tire, showing my new design.

Copies of this patent may be obtained for five cents each, by addressing the "Commissioner of Patents, Washington, D. C."

Fig. 2 is a sectional view on the line 2—2 of Fig. 1, and

Fig. 3 is a diagrammatic view illustrating more in detail my new design.

I claim:

The ornamental design for an automobile tire, as shown.

WILLIAM A. ROBBINS.
